CENTRIFUGAL MACHINE CONTROL
ORGANIZATIONJoseph Hertrich, Hamilton, Ohio, assignor to The
Western States Machine Company, Hamilton,
Ohio, a corporation of Utah

Application June 20, 1947, Serial No. 756,073

3 Claims. (Cl. 192—144)

1

This invention relates to heavy centrifugal machines of the type used in sugar manufacture and more particularly to improved control combinations for high speed suspended centrifugals driven individually by rotary electric motors, such as A. C. induction motors.

An object of this invention is to provide an improved organization of a centrifugal machine driven by a rotary electric motor wherein the driving torque is transmitted through a slip coupling such as a centrifugal clutch, or preferably a hydraulic coupling, and wherein automatically and manually operated controls are provided such that the usual operations of loading, running and stopping the basket and spindle in each operating cycle, together with the desired process operations in the course of each running period, are brought about in the required manner and yet the driving motor normally is kept running at full speed throughout the successive cycles so as to increase the motor operating efficiency and reduce motor requirements and motor heating problems.

Another object of this invention is to provide an improved organization giving the automatic control, the timing and the manual control of operations desired in the use of heavy centrifugals for sugar and similar processing work, wherein new combinations of elements motivated manually, electrically and by fluid pressure are utilized so as to secure the desired conditions and movements of the apparatus with a relatively inexpensive construction which is easy to operate, easy to adjust to suit operating and processing needs, and foolproof under the conditions encountered in sugar centrifugal work.

This invention can make use of various known arrangements of driving motors with slip couplings to transmit the driving torque to the driven elements of the machine, but it is preferred to utilize a driving combination or system as disclosed and claimed in either or both of my United States Letters Patent No. 2,380,595 of July 31, 1945, and my copending application Serial No. 435,023 filed March 17, 1942, now United States Letters Patent No. 2,441,356.

A preferred embodiment is explained in the detailed description which follows, while the improved combinations claimed as this invention are set forth particularly in the appended claims. The description refers to the accompanying drawings, forming a part hereof, in which:

Fig. 1 is a diagrammatic front elevation, partly in section, of a high speed suspended centrifugal machine with its associated elements and controls;

2

Fig. 2 is a wiring diagram illustrating a suitable control circuit for the machine; and

Fig. 3 is a vertical longitudinal cross-section showing the torque control valve assembly as viewed approximately from line 3—3 of Fig. 1.

Referring first to Fig. 1 of the drawings, the centrifugal spindle 20 carries a perforate centrifugal basket 22 at its lower end within a surrounding stationary curb 23, and at its upper end the spindle is suspended within a suitable gyroscopic centrifugal head 24 supported from a suitable hanger 26 depending from framework (not shown). A motor support 30 on the same framework supports driving motor M which has a hollow rotor shaft 32 extending upward to a driving connection with the casing-impeller element 34 of a hydraulic coupling within housing 36 fixed atop the stator-carrying frame 38 of the driving motor. The runner 35 of the hydraulic coupling is disposed within the casing-impeller element 34 and is connected to the top of a central or driven shaft 33 which extends downwardly through the hollow motor shaft 32 to positive mechanical connections with the spindle 20 within head 24. These connections include a flexible coupling of any suitable type by which the spindle and basket are enabled to gyrate under unbalanced loads, in known manner.

A brake drum 52 on the spindle assembly operates with brake bands 53 and 54 which are linked together and to the piston of a fluid pressure cylinder 55 in such manner that fluid under pressure admitted to this cylinder through air line 56 will set the brake bands tightly against the brake drum and bring the spindle assembly to rest from a running condition. The brake bands normally are held away from the drum, in brake "off" or unset position, in well-known manner. Line 56 is fitted with a three-way solenoid valve BSV which normally is positioned so as to vent pressure from cylinder 55, but which is moved to connect line 56 with a source 70 of compressed air or other pressure fluid, and thus cause setting of the brake, when BSV is energized electrically through connections herein-after described.

The hydraulic coupling has discharge ports 39 in the periphery of element 34 through which oil is continuously discharged in the operation of the coupling. The oil so discharged collects in a sump 40 of housing 36, from which it drains through outlet 41 to an oil cooling and re-circulation system (not shown). An oil supply line 42 enters the top of housing 36 and leads fresh oil from the circulation system into the rotary casing-impeller element of the coupling, whence

the oil enters the vortex chamber defined between the oppositely facing impeller and runner elements. Since the hydraulic coupling shown is of the well-known "Vulcan" type, its operation will be understood by those skilled in the art, and it suffices to state that a driving torque is transmitted from the motor M through the hydraulic coupling to the basket-carrying spindle 20 when the motor is running and oil is present in the hydraulic coupling. The value of this torque varies with the relative speeds of, or the slip between, the driving and the driven elements and with the degree of filling, or oil content, of the hydraulic coupling.

The oil supply line 42 has therein a solenoid valve OSV which is normally closed so as to prevent oil flow into the hydraulic coupling. This oil solenoid valve opens when it is energized electrically as occurs through connection hereinafter described. When it is closed with the motor running, any oil present in the hydraulic coupling becomes quickly discharged through the ports 39, so that the torque transmission and driving action through the hydraulic coupling are thus discontinued.

A torque control valve 44 also can be provided in the oil supply line for the purpose of adjustably regulating the accelerating torque of the machine. This valve is normally held open so as to provide free passage for the inlet oil from branch 42a to branch 42b of supply line 42, by means of a compression spring 46 or a fluid or hydraulic pressure system which urges the movable valve element 41 to valve open position under a constant control force. On the other hand, an arm 48 extends radially from the motor frame 38 and is positioned to engage the movable valve element and urge it toward closed position, in opposition to the control force, under the torque reaction of the motor M which is exerted by having the stator-carrying frame 38 mounted on motor support 39 for limited turning movement. The motor frame preferably is so mounted by means of a circular series of ball bearings 40 between it and the support 39 and by slightly enlarging the holes in the frame through which bolts 50 extend to hold the motor to its support. This torque control system, which is described more fully in the aforesaid application Serial No. 435,023, gives the machine a constant yet adjustable rate of acceleration and brings about other advantages in its use.

The apparatus as shown is provided also with means for washing the centrifugal basket 22 or its contents at appropriate times in the centrifugal operating cycles and with means for separating resulting wash liquid received on the wall of curb 23 from liquid of different characteristics centrifuged from the basket contents. These means per se are not a part of the invention herein claimed, but they are shown and described in order to illustrate the adaptability of the control organization of this invention to a machine in which there is coordinated control of the actions of driving, braking, washing and liquid separating means, as well as to a machine in which the washing and separating means may be eliminated from the basic control organization or may be arranged only for independent hand operation.

The washing means as shown comprise a sprayer 60 of known construction extending from a bracket 61 on the top of curb 23 downwardly into a position within the confines of basket 22, and a pipe 62 through which hot water or other

suitable washing fluid is delivered to the sprayer. This pipe is fitted with a solenoid valve WWSV, which normally is held closed so that the sprayer is "off," but which opens to cause spraying or washing action when WWSV is energized electrically through connections hereinafter described.

The liquid or syrup separating means as shown is the "curb" or "ring valve" type disclosed in United States Reissue Patent 22,772 of Eugene Roberts. Annular partition 64 divides the bottom of curb 23 into inner and outer annular troughs. On the curb wall overlying the outer trough is an inclined annular ledge 65 upon which a vertically movable annular syrup deflector 66 may be seated. The inner portion of this deflector ring extends inwardly to overlie the top portion and inner side of partition 64. When the deflector is seated its outer edge seals with ledge 65 to form an uninterrupted syrup-conducting platform extending from the inside of curb wall 23 into the inner trough. When, however, the deflector is raised, the said platform is interrupted to form an annular passage between the outer edge of deflector 66 and ledge 65, through which passage wash syrup or other liquid then flowing down the curb wall is entrapped into the outer trough.

The shifting of the deflector ring to its seated and its unseated positions, respectively, occurs through a series of connections from the ring through the base of the curb to the pistons of air cylinders 68 mounted on the exterior of the curb. Only one of these several units is shown. They normally hold ring 66 in its raised or unseated position away from ledge 65, and they are connected to a fluid pressure line 69 through which compressed air or other suitable pressure fluid may be admitted to the cylinders 68 from a three-way solenoid valve SSSV and compressed airline 70. The valve SSSV is arranged in known manner so that it normally is open to transmit compressed air into line 69, thus holding the deflector ring 66 seated on ledge 65; while energization of valve SSSV through electrical connections hereinafter described closes off the air pressure and connects line 69 with vent 71 so that springs in cylinders 68 then move the deflector ring 66 to its raised or unseated position.

The control of the operations of the machine is centered at a manually operated switch station 59 convenient to the centrifugal attendant. In the preferred embodiment this switch station comprises a master switch MS and push-button units PB1 and PB2.

PB2 is a unit of well-known construction having two interlocked switches controlled by buttons 81 and 82. These switches are connected electrically with a control relay CRM which in turn is connected electrically with a motor starter 83 for connecting the driving motor M with its power supply lines 84. Common electrical elements and connections may be employed such that upon depressing switch button 81 a control circuit is closed which energizes relay CRM, which in turn energizes the motor starter 83, and causes it to make motor energizing connections between the motor M and the power supply lines 84. Upon depressing pushbutton 82 the motor M is deenergized through deenergization of relay CRM and starter 83.

Pushbutton unit PB1 likewise comprises two interlocked switch elements positioned by buttons 85 and 86. These elements have electrical connections to one supply line 101 for control

current and to conductors 110 and 111 which may extend from a junction box JB. Conductor 110 and the other control current supply line 102 lead from the junction box to the washing or sprayer valve WWSV, while line 102 and conductor 111 lead from the junction box to the separator valve SSSV. The wiring of the switch elements is such that depressing button 85 energizes valves WWSV and SSSV, while depressing button 86 deenergizes them, as appears in the elemental wiring diagram of Fig. 2. Thus, button 85 constitutes a "Wash" button, the pushing of which causes washing or spraying action with simultaneous movement of the deflector ring 66 to its unseated position, while button 86 is a "Stop Wash" button the pushing of which terminates the washing or spraying action and causes the deflector ring to be reseated in sealing engagement with ledge 65.

The master switch MS is utilized for the control of the normal cycles of operation of the machine, and to this end it has electrical actuating connections with the hydraulic coupling filling control device (oil solenoid valve OSV), with control device BSV of the brake setting means, and with adjustable electrical timing mechanism shown diagrammatically at T in Fig. 1. When desired, the washing and separator control devices WWSV and SSSV, respectively, are connected through conductor branches 110a, 110b and 111a for actuations through contacts of the timing mechanism T which connect the respective branches to current supply line 101, so that all the operations in normal cycles of operation of the machine may take place in desired sequence in response to movements of the master switch MS.

Master switch MS is preferably a drum type switch of known construction having a rotary switch element or drum carrying contact segments and movable by a handle 90 which can assume several different angular positions corresponding to different circuit conditions and different operating conditions of the machine. As shown, the switch has "brake," "off," "load" and "run" positions at which the contact segments hold their respective circuits either open or closed as appears from the diagram in Fig. 2.

As there diagrammed the master switch segments include a wide drive control segment MR, shunted timer control segments MT₁ and MT₂ and a narrow brake control segment MB.

Segment MR is adapted to bridge contacts to connect control current supply line 101 with conductor 104 which leads through a normally closed contact CR₁ of control relay CR and through conductor 104a to the coil of solenoid valve OSV, the other lead of this coil being connected with current supply line 102 so that valve OSV is energized and open when MR is active.

Shunted master switch segments MT₁ and MT₂ are adapted to bridge contacts to connect line 101 with conductor 105, which leads to the clutch coil TC of timer T and also through timer switch T₀ (which closes with the energization of TC) to the timer motor TM. Since TC and TM are permanently connected with line 102, the closing movement of segments MT₁ and MT₂ energizes and thus starts action of the timer, while opening movement of these segments deenergizes the timer and causes it to reset.

The narrow master switch segment MB is

adapted to bridge contacts to connect line 101 with conductor 103 which leads to the coil of brake solenoid valve BSV; and since the other lead of this coil is connected to line 102 the movements of MB energize and deenergize, thus opening and closing, this valve.

In the "off" position of the master switch, as it appears in Fig. 2, all the master switch circuits are open. When handle 90 is moved one step to the right to the "Load" position, the switch segments shift one step to the left, where segment MR closes its circuit from 101 through 104, CR₁ and 104a to OSV, and torque is then delivered through the hydraulic coupling from the running motor M to the spindle 20 to start the machine. The other master switch circuits remain open at this position.

When the master switch segments are moved two steps to the left from the "off" position of Fig. 2, handle 90 in Fig. 1 being moved to the "run" position, segment MR makes the same drive activating circuit as above described, and at the same time segments MT₁ and MT₂ make a timer activating circuit from 101 through conductor 105 to the clutch coil TC and motor TM of the electrical timer T. At this position of the master switch, therefore, the driving system is active to accelerate and run the basket and the timer is active. The timer then takes over the control of further operation in the normal cycle of the machine, as presently will be described.

Whenever the master switch handle 90 is moved to the "brake" position, the switch segments are positioned one step to the right of their "off" position, so that the drive and timer control circuits are opened to inactivate the hydraulic coupling and reset the timer, while the brake is set because MB closes its circuit from line 101 through 103 to open BSV. Air pressure then acts in cylinder 55 to force brake bands 53 and 54 against brake drum 52. Movement of the master switch to "brake" position thus provides for emergency stopping of the machine.

The timer mechanism T is an adjustable timing system comprising at least one timer switch element arranged to be moved at a predetermined time after the mechanism is activated, according to its setting, so as to discontinue the driving action upon the spindle and activate the brake setting means of the machine. Further timer switch elements also are included in the illustrated embodiment with connections to the washing and syrup separating means, respectively, whereby these means are actuated at adjustably predetermined times in relation to the starting of the timer mechanism and the concomitant starting of the acceleration or running period of the machine. The several timer switch elements may be provided by several interconnected individual timers or time delay switches of known construction, or by a composite timer unit having a single motivating mechanism arranged to move the respective switch elements in adjustably timed relation to the starting or energization of said mechanism. The latter arrangement is preferred, and for this purpose a composite multi-switch unit of the type known as the "Multiflex" timer may be used; for example, a construction as shown in U. S. Patent No. 2,175,864.

Such a composite timer mechanism appears in Fig. 1. Its known construction (not shown in detail) includes clutch coil TC and timer motor TM of diagram Fig. 2, as well as the timer

motor switch T_0 and, in this case, four individually timed switches T_1 , T_2 , T_3 , and T_4 . For each of these switches there is an "on" detent and an "off" detent which respectively are adjustable in relation to a timing scale shown on the face of the unit so that a timed action or circuit change will occur at any desired interval in relation to the starting of the mechanism, according to the setting of the respective detents. If the "on" detent is placed at the upper limit of its scale, the corresponding circuit or contact is closed when the timer is energized. If the "off" detent is placed at the lower limit of its scale, the corresponding circuit or contact, after having been closed according to the setting of the "on" detent, will stay closed until the timer is deenergized or reset.

According to the diagrams in Fig. 1 and Fig. 2, the "on" detent of timer switch T_0 is placed at the top of its scale and this switch, located across conductor 105 leading to timer motor TM , is closed so that the timer motor becomes active when the mechanism is energized through master switch segments MT_1 and MT_2 (at the "run" position of the master switch). The "off" detent of element T_0 is placed slightly above the lower limit of its scale, say at 10 seconds less than a 5 minute setting, so that the timer mechanism inactivates its own motor if not reset after an abnormally long period—the normal period of timer activity being less than 4 minutes in the use here assumed by way of illustration.

Timer switch element T_1 is in the circuit from current supply line 101 to conductor 109 , so that the closing of this element energizes relay CR . CR then opens its CR_1 contacts and closes its CR_2 contacts with the result of discontinuing the driving action through the hydraulic coupling and setting the brake to stop the rotation of the spindle assembly. Timer switch elements T_3 and T_4 are in the circuits leading from line 101 through branch conductors $110a$ and $110b$ respectively to conductor 110 and the coil of valve $WWSV$, so that these timer elements may be closed independently to initiate separate washing periods, and may be opened to terminate such periods. Timer switch element T_2 is in the circuit from line 101 to branch conductor $111a$ which leads to conductor 111 and the coil of valve $SSSV$, so that the closing and opening movements of element T_2 result in energization and deenergization of the syrup separator control device $SSSV$ with consequent raising and lowering, respectively, of the deflector ring 66 .

To illustrate the timer settings, it may be assumed that the machine is to be used for processing a sugar massecuite which is to be subjected to a preliminary washing of about 10 seconds duration, to begin 15 seconds after starting the acceleration or running period of the loaded centrifugal basket; followed 20 seconds later (45 seconds after starting) by a second washing period of 15 seconds duration; followed in turn by a drying period of 70 seconds at the end of which the drying action is to be discontinued and the brake set to stop the machine. The syrup separator is to be unseated 5 seconds after starting the second washing period, so that wash syrup received then and afterward on the curb wall 23 will be collected in the outer trough of the curb button.

In such a case, the "on" detent of element T_1 is set on its scale at a point corresponding to 2 minutes and 10 seconds, while the "off" detent

is left inactive at the bottom of the scale. The "on" detent of element T_2 is set at a 50 second interval from the top of its scale, the corresponding "off" detent being placed at the bottom. The "on" and "off" detents of element T_3 are set at intervals of 15 and 25 seconds respectively from the top of their scale, and the "on" and "off" detents of element T_4 are set at 45 and 60 second intervals respectively from the top of their scale. As has been described, the timer mechanism T is started in action by movement of master switch handle 90 to its "run" position. Element T_0 closes at that time, while elements T_3 , T_4 , T_2 , and T_1 close in sequence at predetermined times thereafter, according to the settings of their respective "on" detents, and open at times determined by the settings of their respective "off" detents.

The complete operation of the machine may be further described as follows:

When beginning the use of the machine after a shutdown period, button 84 of switch PB_2 is depressed to energize relay CRM and motor starter 83 and thus start the operation of the driving motor M , the master switch being at its "off" position so that OSV is deenergized, the hydraulic coupling is empty and the motor runs freely without driving the machine.

Assuming the basket 22 to be empty, the operator now moves the master switch to its "load" position and holds it there until the spindle and basket have reached a low speed of rotation desired for loading the basket, which usually is about 200 R. P. M. This movement of the master switch closes the circuit from line 101 through conductor 104 , the normally closed contact CR_1 of relay CR and branch conductor $104a$ to the coil of OSV , so that oil flows through OSV and line 42 into the hydraulic coupling, filling the coupling and causing the motor M to transmit torque to the basket-carrying spindle.

When the desired loading speed is reached, the operator may return the master switch to "off" position and then load the basket in the usual way, or he may jog handle 90 between its "load" and "off" positions to hold a desired loading speed, or he may move handle 90 to its "run" position and then start the loading so that loading occurs in part of the acceleration period of the machine. The movement to the "run" position occurs, in any event, to start the acceleration or running period of the machine; at which time the driving system is activated, because master switch segment MR closes its circuit to OSV , and the timer mechanism is activated simultaneously because master switch segments MT_1 and MT_2 close their circuit through conductor 105 to the timer coil TC and the timer motor TM .

The machine then proceeds to accelerate on its running period under the control of timer T , and the operator may attend to another machine while the automatic phase of the operating cycle runs its course. By reason of the torque control system centered at valve 44 , the acceleration takes place at a constant rate under a constant accelerating torque that can be adjusted by adjustment of the compression of spring 46 . At an interval of 15 seconds after movement of the master switch to "run" position, the timer closes its switch element T_3 , which starts the first washing period by energizing valve $WWSV$ through branch conductor $110a$ and 110 . Ten seconds later the timer opens element T_3 , so that the first washing

period ends. After another 20 seconds, the timer closes element T4 to start the second washing period, WWSV being then energized through conductor 110 and branch conductor 110b. After another 5 seconds, or 50 seconds after starting the timer, the timer closes its switch element T2, which energizes SSSV through branch conductor 111a and conductor 111. Prior to this action, the syrup centrifuged from the contents of basket 22 has passed from curb wall 23 over ledge 65 and deflector 66 into the inner trough of the curb bottom, and the energization of SSSV causes the deflector to be raised so that wash syrup thereafter received on the curb wall flows between the ledge and the deflector into the other trough of the curb bottom.

The timer opens switch element T4 10 seconds after the shifting of the syrup separator, and the machine then proceeds on the drying phase of its cycle at its full running speed. This continues for 70 seconds, until 130 seconds after starting the running period, whereupon the timer closes its switch element T1 to bring about the stopping of the basket. Thus OSV is de-energized, with the effect of discontinuing the driving action through the hydraulic coupling, and BSV is energized to admit compressed air from line 70 into line 56 and the brake setting cylinder 55, which applies the brake to stop the rotation of the spindle assembly. During all these operations, the driving motor M continues to run at full speed, pushbutton PB2 being left undisturbed throughout all the normal cycles of the machine.

The operator now returns to the machine and attends to discharging the processed sugar from basket 22 by moving master switch handle 90 to "load" position until the basket has reached a desired discharging speed and then manipulating a discharger (not shown) in the usual manner. Then the basket is brought again to the desired loading speed, and another charge is loaded to start another cycle which proceeds in the manner described above.

Sometimes it is desirable to clean the basket by washing it after the discharging operation, and for this purpose the operator may use buttons 85 and 86 of pushbutton unit PB1. Depressing button 85 starts operation of the sprayer and depressing button 86 terminates its operation.

If abnormal or emergency stopping of the basket is desired at any time during its rotation, the operator may simply move master switch lever 90 to the "Brake" position. This energizes BSV to set the brake and at the same time de-energizes relay CR and timer T so that the driving action through the hydraulic coupling is discontinued and the timer is reset to its starting position in the usual manner.

If abnormal or emergency stopping of the driving motor M is desired at any time, the operator may simply depress button 82 of PB2. A handle 57 is provided on the brake setting mechanism, so that the brake can be applied by hand at any desired time, in case failure occurs in the electrical control system.

It is to be understood that the detailed description and the accompanying drawings are illustrative and that the improvements herein disclosed may be embodied in various forms of construction within the scope of the appended claims.

I claim:

1. In a centrifugal machine comprising a

5 basket-carrying spindle, rotary driving means including an electric motor and a hydraulic coupling connected to transmit torque from said motor to said spindle, and a brake having brake setting means connected to stop rotation of said spindle, said brake setting means including an air cylinder, an air pressure line connected to said cylinder and a solenoid valve normally closing said line, motor switch means connected
 10 with and movable to energize and deenergize said motor, an oil supply line leading into said coupling having a solenoid valve normally closing said line, said coupling having means for continuously discharging oil therefrom, adjustable electrical timer mechanism comprising at least one switch moved at a predetermined time after the timer is activated, according to its setting, a master switch movable manually to different positions, electrical connections from said master
 15 switch to said oil solenoid valve and said timer mechanism, respectively, operative at one position of said master switch to open said valve and activate said time mechanism simultaneously, and electrical connections from said timer switch
 20 to said oil solenoid valve and said air solenoid valve respectively, responsive to the timed movement of said timer switch to close said oil solenoid valve and open said air solenoid valve simultaneously, whereby after a predetermined period of running the machine the basket-carrying spindle is automatically stopped while the master switch is at said position and while the driving motor may continue energized and running.

2. In a centrifugal machine comprising a basket-carrying spindle, rotary driving means including an electric motor and a hydraulic coupling connected to transmit torque from said motor to said spindle, and a brake having brake setting means connected to stop rotation of said spindle, said brake setting means including an air cylinder, an air pressure line connected to said cylinder and a solenoid valve normally closing said line, motor switch means connected with and movable to energize and deenergize said motor, an oil supply line leading into said coupling having a solenoid valve normally closing said line, said coupling having means for continuously discharging oil therefrom, a torque control valve in said oil line having means for applying thereto a predetermined force tending to open the same, said motor having its stator-carrying frame mounted for limited turning movement and an arm extending from said frame to urge said torque control valve toward closed position according to the torque reaction of said motor, timer mechanism comprising at least one switch moved at a predetermined time after the timer is activated, according to its setting, a master switch movable manually to different positions, electrical connections from said master switch to said oil solenoid valve and said timer mechanism, respectively, operative at one position of said master switch to open said valve and activate said timer mechanism simultaneously, and electrical connections from said timer switch to said oil solenoid valve and said air solenoid valve respectively, responsive to the timed movement of said timer switch to close said oil solenoid valve and open said air solenoid valve simultaneously, whereby after a predetermined period of running the machine the basket-carrying spindle is automatically stopped while the master switch is at said one position and while

11

the driving motor may continue energized and running.

3. In a centrifugal machine comprising a basket-carrying spindle, a rotary driving means including an electric motor and a hydraulic coupling connected to transmit torque from said motor to said spindle and a brake having brake setting means connected to stop rotation of said spindle, said brake setting means including an air cylinder, an air pressure line connected to said cylinder and a solenoid valve normally closing said line, motor switch means connected and movable to energize and deenergize said motor, an oil supply line leading into said coupling having a solenoid valve normally closing said line, said coupling having means for continuously discharging oil therefrom, adjustable electrical timer mechanism comprising at least one switch moved at a predetermined time after the timer is activated, according to its setting, a master switch movable manually to several different positions, electrical connections from said master switch to said oil solenoid valve, said timing mechanism and said air solenoid valve, respectively, said master switch holding all said connections open at one position, at a second position closing connections only to open said oil solenoid valve, at a third position closing connections only to open said oil solenoid valve and activate said timer mechanism, and at a fourth position closing connections only to open said air solenoid valve, whereby while said motor is energized said master switch may be moved manually to cause driving action upon the spindle through said coupling

12

without action of the timer, or to run the machine with driving action upon the spindle through the coupling and concurrent action of the timer, or to discontinue the driving and timer actions and set said brake, or to open all said connections so that the machine idles without driving, timer or brake action, and electrical connections from said timer switch to said oil solenoid valve and said air solenoid valve, respectively, interconnected with the aforesaid connections and responsive to the timed movement of said timer switch to close said oil solenoid valve and open said air solenoid valve simultaneously, whereby after a predetermined period of running the machine the basket-carrying spindle is stopped while the master switch is at said third one position and while the driving motor may continue energizing and running.
